UNITED STATES PATENT OFFICE.

WILLIAM WHARTON, JR., OF PHILADELPHIA, PENNSYLVANIA, ASSIGNOR
TO WILLIAM WHARTON, JR., & COMPANY, INCORPORATED, OF SAME
PLACE.

RAILROAD-SWITCH.

SPECIFICATION forming part of Letters Patent No. 674,327, dated May 14, 1901.

Original application filed October 25, 1900, Serial No. 34,371. Divided and this application filed March 25, 1901. Serial No. 52,866.
(No model.)

To all whom it may concern:

Be it known that I, WILLIAM WHARTON, Jr., a citizen of the United States, residing in Philadelphia, Pennsylvania, have invented 5 certain Improvements in Railroad-Switches, of which the following is a specification.

My invention relates to certain improvements in railroad - switches of the type in which the track of the main line is unbroken.

10 My invention relates to certain improvements in switches with unbroken main-track rails shown and described in the patents granted to me, No. 69,599, dated October 8, 1867, and No. 357,438, dated February 8, 1878, 15 in which is shown and described a guard-rail attached to and movable with the pointed switch-rail and also an elevating-rail movable therewith.

The object of my invention is to insure the 20 transfer of a car from the siding or turnout rails to the rails of the main track, and vice versa.

This application is a division of an application filed by me on the 25th day of October, 25 1900, Serial No. 34,371, allowed January 17, 1901.

In the accompanying drawings, Figure 1 is a diagram plan view illustrating my improved railroad - switch, showing the switch - rails 30 thrown over in contact with the main-line rails. Fig. 2 is an enlarged section on the line 2 2, Fig. 1. Fig. 3 is an enlarged section on the line 3 3, Fig. 1.

A A' A² are the permanent rails of the main 35 track.

B B' are the rails of the siding or turnout. D D' are the switch-rails, and E is the extended guard-rail.

The pointed switch-rail D from its end d 40 to the line d' is upwardly inclined, so as to carry the wheels of the car up to the elevated portion of the rail, and for a portion of its length has its head overlapping a portion of the main-line rail A, as clearly shown in Fig. 45 and in the cross-sectional view, Fig. 2. This overlapping of that rail has for many years been common in switch structures of this type. Adjacent to the pointed rail is the guard-rail E and between this guard-rail and 50 the pointed rail, in the present instance, are

spacing-blocks c, and the two rails D and E are secured together by bolts or other suitable fastenings.

It will be noticed that the guard-rail E extends a considerable distance beyond the point or end d of the switch-rail D and that when in the position shown in Fig. 1 that portion of the guard-rail extending beyond the point of the switch-rail D is parallel with the main-line rail A. This extension of the guard-rail beyond the end or point of the switch-rail D insures the proper transfer of the car-wheels from the siding or turnout rails to the rails of the main track.

The upper surface of that portion of the 65 guard-rail E which is attached to the pointed rail D is preferably made to conform with the varying heights of the upper surface of the rail D, and the upper surface of that portion of the guard-rail E which extends beyond the 70 point of the switch-rail D is preferably made of the same height as the upper surface of the main-track rail A.

The outside elevating-rail D' bears against the main-line rail A². The rail A² is rolled 75 with a head narrower than the head of the other main-track rails, as clearly shown in Fig. 1, thus allowing the elevating-rail D' to be moved more nearly into the path of the car-wheels traversing the switch, so that when 80 the switch structure is in the position shown in Fig. 1 the car-wheels will be more surely transferred from the main-line rail to the siding-rail or from the siding-rail to the main-line rail, as the car-wheels will have more of 85 their tread-surface extending outside of the main rail and available for bearing upon the switch-rail D' than would be the case if the head of the main rail at that place was of the normal width.

I extend the outside elevating-rail D' beyond the pointed end of the switch-rail D and preferably to a point nearly opposite the end of the guard-rail E, and I connect the guard-rail E to the outside elevating-rail D' 95 by tie-rods f, so that by this construction the outer end of the guard - rail E is supported laterally by the extension of the outside elevating-rail D'.

The upper surface of the head of the out- 100

side elevating-rail D' at its movable end and for a certain distance therefrom is level with the upper surface of the head of the main-line rail A²; but from about a point b to about 5 a point b' it is upwardly inclined, and the remaining length of the rail is elevated above the surface of the main-line rail. This construction is clearly shown in the sectional views Figs. 2 and 3.

10 I do not claim, broadly, in conjunction with unbroken main-line switches, a guard-rail secured to and movable with the pointed switch-rail, as this is clearly illustrated and described in the patents above mentioned, nor do I 15 claim the inclined elevation of the pointed switch-rail and the inclined elevation of the outside elevating-rail in combination with such a guard-rail, as this construction is clearly described in the Patent No. 110,808, 20 granted to me January 3, 1871.

I claim as my invention—

1. The combination in a railroad-switch, of the unbroken main-track rails, the rails of the siding or turnout and a movable switch-25 structure consisting of an outside elevating-

rail, a pointed rail and a guard-rail alongside of and attached to the pointed rail; the head of the main-track rail against which the outside elevating-rail is moved being of less width than the heads of the other rails of the 30 main track, substantially as described.

2. The combination in a railroad-switch, of the unbroken main-track rails, the rails of the siding or turnout and a movable switch structure consisting of an outside elevating-rail, a pointed rail and a guard-rail alongside of and attached to the pointed rail and extending beyond its pointed end; the head of the main-track rail against which the outside elevating-rail is moved being of less width 35 40 than the heads of the other rails of the main track, substantially as described.

In testimony whereof I have signed my name to this specification in the presence of two subscribing witnesses.

WILLIAM WHARTON, JR.

JOS. H. KLEIN.

Correction in Letters Patent No. 674,327.

It is hereby certified that in Letters Patent No. 674,327, granted May 14, 1901, upon the application of William Wharton, Jr., of Philadelphia, Pennsylvania, for an improvement in "Railroad-Switches," an error appears in the printed specification requiring correction, as follows: In line 14, page 1, the date, "February 8, 1878," should read *February 8, 1887*; and that the said Letters Patent should be read with this correction therein that the same may conform to the record of the case in the Patent Office.

Signed, countersigned, and sealed this 28th day of May, A. D., 1901.

[SEAL.]

F. L. CAMPBELL,
Assistant Secretary of the Interior.

Countersigned:

F. I. ALLEN,
Commissioner of Patents.
